His Attorney.

UNITED STATES PATENT OFFICE.

GEORGE E. STARIE, OF SCHENECTADY, NEW YORK, ASSIGNOR TO GENERAL ELECTRIC COMPANY, A CORPORATION OF NEW YORK.

TIME-ELEMENT DEVICE AND MOTOR-CONTROL SYSTEM EMPLOYING THE SAME.

Application filed May 4, 1925, Serial No. 28,036. Renewed January 24, 1929.

My invention relates to an improved electro-responsive time element device for general purposes, and in particular to an electromagnetic time element device for controlling the 5 operation of a motor controlling switch after the operation of another motor controlling switch.

My invention also relates to an improved 10 motor control system employing the improved time element device of the invention for obtaining the desired succession of operation of motor controlling switches or contactors with a desired time interval interposed between the operation of successively operated contacts.

The present application is directed to improvements of and is covered by a copending application of Eugene R. Carichoff and Benjamin W. Jones, Serial No. 527,520, filed Jan. 20, 1922, a renewal of an application, Serial No. 354,030, filed Jan. 26, 1920.

Time element control of electromagnetic switches, as heretofore proposed, has left something to be desired in the way of a simple, reliable and effective device which invariably gives the desired time interval of operation. Motor control systems operating on the time element principle, as heretofore proposed, have also left something to be desired in that complications are introduced which render the system uncertain in operation.

In carrying my invention into effect, I employ an electromagnetic time element device 35 of very simple construction, and one which when employed in a motor control system, for example, makes possible a very simple, effective and reliable system for producing the intended control of the motor. The electromagnetic time element switch is provided 40 with a magnetic structure with a winding thereon and a magnetic movable element armature carrying a switch contact, the armature being biased to the unattracted position and the switch contact carried by the armature being biased to a definite position, as for 45 example, the closed position. The armature of the electromagnetic time element device is biased to the unattracted position by any suitable means such as a spring, the tension of which may be adjusted so that when the armature is in the attracted position, it is magnetically held in that position against the action of the spring tending to move the armature to the unattracted position. The wind-

ing of the electromagnet is connected so as to be shunted when a previously operated switch is closed. By reason of the fact that the winding has a considerable inductive effect, the short-circuiting of the winding will permit the induced current to maintain a magnetic flux in the magnetic structure of the electromagnet and thus maintain the armature in the attracted position for an appreciable interval of time. The winding is provided with a sufficient number of turns so that with the armature in the attracted position, the magnetic flux of the relay will be considerably in excess of that required to hold the armature in the attracted position, thus insuring that the time interval introduced will not be appreciably affected by such variables as variations of the supply circuit potential or variations of the heating of the winding. Adjustment of the time element is obtained by adjusting the air gap between the armature and the core of the electromagnet, and this is preferably done by mounting a shim of non-magnetic material on the armature so that when the armature is magnetically operated to the attracted position, the shim will insure that there will be a definite and invariable air gap between the armature and the pole face. The time interval may be very accurately adjusted to the desired value by employing a shim of the correct thickness for the particular time interval desired. The time interval is also adjusted by varying the tension of the spring which biases the armature to the unattracted position, since the time interval is obtained by the pull of the induced flux of the electromagnet overpowering the strain of the spring tending to move the armature to the unattracted position. The adjustment obtained by varying the strain of the spring is quite accurate and is simply obtained so that as a practical matter, after a suitable thickness of shim has been determined, the principal adjustment will be by varying the spring tension.

For a better understanding of the invention, reference is had to the accompanying drawing in which Fig. 1 is a very simple diagram of a time element motor control system in accordance with the invention, Fig. 2 is a side view of an electromagnetic time element relay in accordance with the invention, and Fig. 3 is a front view of the same.

Referring first to Figs. 2 and 3, it will be seen that the time element switch or relay

comprises an electromagnet structure includ- 5 ing the strap of magnetic material 10 and the core 11 of magnetic material on which the winding spool 12 is mounted. The strap 10 and the core 11 are secured in any suitable manner to an insulating supporting base, as for example, by means of the bolt 13. The magnetic movable element or armature 14 of the device is pivotally mounted with respect to 10 the strap 10 and is biased to the unattracted position by means of the spring 15. This spring is mounted on a bolt 16, which is carried by the support 17 secured to the strap 10.

The nut 18 is provided for adjusting the 15 tension of the spring 15 and thus varying the time interval of operation of the device. The shim 19 of non-magnetic material is secured to the inner face of the armature 14 so as to make abutting engagement with the end of the 20 pole face 11 when the armature is in the attracted position, thus introducing a definite and invariable air gap between the armature and the pole when the armature is in the attracted position.

25 The armature carries a contact 20 at its lower end thereof, and this contact is arranged to make engagement with the stationary and adjustable contact 21. The contact 21 is carried by means of a strap of electrical conduct- 30 ing material 22, which is secured to the insulating support by means of the bolt 23. The arrangement is such that a single winding on the electromagnetic device controls the entire operation thereof and this winding has a 35 sufficient number of turns so that with the armature in the attracted position the magnetic flux of the electromagnet is considerably in excess of that required to maintain the armature in the attracted position. When 40 the winding 12 is short-circuited, the inductive effect of the electromagnet is employed to maintain the armature in the attracted position for an appreciable interval of time, and by reason of the fact that the holding flux 45 was considerably in excess of that required to maintain the armature in the attracted position, this time interval will not be appreciably affected by the variables which affect previous time element devices, namely, variations 50 of the supply circuit potential and variations of the heating of the winding.

In Fig. 1, the electric motor having an armature 24 and a series field winding 25 is arranged to be connected to the direct current supply circuit 26 by means of the pair of 55 directional contactors 27 and 28 for the forward direction of motor operation and the pair of directional contactors 29 and 30 for the reverse direction of motor operation. The line contactor 31 is provided for opening the 60 motor circuit upon failure of power and the connections are such that the master controller 32 must be returned to the "off" or neutral position in order to reclose this contactor.

65 The current taken by the motor is limited

by means of resistance in the motor armature circuit. This resistance comprises the plugging resistor 33 controlled by the plugging contactor 34 and the accelerating resistors 35 and 36 controlled by the accelerating 70 contactors 37 and 38, respectively. The plugging contactor 34 is under the control of a plugging relay 39. This relay is intended primarily to delay the energization of the plugging contactor 34 upon a rapid reversal of the 75 motor by the well-known plugging action, and the relay is provided with a winding 40 for determining the sequence of the closing of the plugging contactor 34 with reference to other 80 parts of the system. The winding 41 is connected across the resistors 33 to 36 so as to give a current limit control for this relay.

The accelerating resistor contactor 37 is controlled by means of the time element relay 42, of the construction shown in more detail 85 in Figs. 2 and 3. In general it may be said that this relay is provided for giving a time interval of operation after the closing of the plugging contactor 34, dependent practically entirely on the inductive effect of the relay 90 when the winding of the relay is shunted in response to the shunting of the plugging resistor 33.

As thus constructed and arranged, and with the parts in their respective positions 95 indicated in Fig. 1, the operation of the system is as follows: The disconnecting switch 43 in the main motor circuits, and the disconnecting switch 44 in the control circuits will first be closed. The closing of the disconnecting switch 44 will cause the line contactor 31 to be energized to close, the circuit being from the positive supply conductor, segment 45 of the master controller 32 and segment 46 of this controller, through the winding of contactor 31 to the negative supply conductor. The line contactor 31 in closing, will also close the auxiliary switch 47, thereby establishing a maintaining circuit for the line contactor and permitting the master controller to be moved 100 out of the "off" position without affecting the energization of the line contactor.

It will also be observed that when the disconnecting switch 44 is closed, the winding of the relay 42 will be energized across the supply circuit with the resistor 48 in series with the relay winding, and that the winding 40 of the relay 39 will also be energized across the supply circuit with the resistor 49 in series with the relay winding. These two relays will therefore be energized to open their respective contacts, preparatory to later operating to produce the intended control of the motor. If now the master controller 32 is thrown to the full running position forward (the master controller thrown to the left final position), the directional contactors 27 and 28 will first be closed, thereby connecting the motor to the source of supply for forward direction of motor operation, the coils 105 110 115 120 125 130

of contactors 27 and 28 being energized through the segments 46 and 50 of the master controller. The directional contactor 27 will close its auxiliary contacts 51 and thus shunt the winding 40 of the relay 39 so as to place this relay under the control of the winding 41 which is now energized responsively to the voltage drop across the resistors 33 to 36 inclusive. The closing of the directional contactor 28 will simultaneously close the auxiliary switch contacts 52, thereby partially completing a circuit for the winding of the plugging contactor 34, the circuit being from the negative supply conductor, winding of contactor 34, segments 53 and 54 of the master controller 32, to the contacts of the relay 39, but since these contacts are temporarily at least maintained open, the closing of the auxiliary switch contacts 52 will not effect the energization of the plugging contactor 34. However, as soon as the motor current has dropped to the predetermined value, the winding 41 of relay 39 will be unable to hold the relay contacts in their open position against the strain of the spring 55 and this relay will close, energizing the plugging contactor 34 to close through the circuit previously traced and the segments 50 and 46 of the master controller and the auxiliary switch 47 to the positive supply conductor.

When the plugging contactor closes, it also closes its auxiliary switch contacts 56, thereby shunting the winding of relay 42. As previously explained, this relay is of the construction illustrated in more detail in Figs. 2 and 3. Although the relay winding has been shunted, the relay will not release its armature for an appreciable interval of time, due solely to the inductive effect of the relay winding. When the magnetic holding effect of the flux of the induced current is overcome by the biasing spring of the relay, the relay will very quickly close its contacts, thereby energizing the winding of the resistor contactor 37 through a circuit from the negative supply conductor, contacts of relay 42, winding of contactor 37, segment 57 of master switch 32, segment 54 of the master switch, contacts of relay 39, auxiliary switch 52, segments 50 and 46 of the master switch auxiliary switch 47 to the positive supply conductor. Contactor 37 in closing also closes its auxiliary contacts 58, thereby energizing the resistor contactor 38 to close. The resistor 36 will ordinarily be of comparatively small value as compared to the resistors 35 and 33 so that the time interval of operation of the closing of the contactor 38 after the contactor 37 will be sufficient for certain applications. In case it is desired to reverse the motor very quickly and employ the plugging feature of the control, the master controller is thrown from the final position forward to the final or any intermediate position reverse. It will be assumed that the controller is

thrown to the full reverse position, since those skilled in the art will readily understand the operation in case the controller is merely thrown to an intermediate position, from an understanding of the operation when full reversal is had.

When the master controller moves out of its third operative forward position, the accelerating contactors 37 and 38 are directly deenergized and opened and when the master controller moves out of its second operative position forward, the plugging contactor 34 will be deenergized and opened. The introduction of the resistance in the motor armature circuit will cause the winding 41 of the relay 39 to be again momentarily energized in accordance with the drop in potential across the resistors 33 to 36, inclusive, and the opening of the auxiliary switch 56 will remove the shunt about the winding of relay 42 so that relays 42 and 39 will both open. The relay 39 will have a further opening effect applied thereto by the energization of the winding 40 in response to the opening of the auxiliary switch contacts 51 of directional contactor 27 when the master controller is moved out of its first operative forward position to the neutral position. It may be said at this time that while the above stated operation has been assumed to be taking place at a certain definite sequence, this has been done merely for the purpose of explanation of what could be the case but which is not necessarily in all cases the exact sequence, since if the master controller is thrown very quickly from the full forward position to the full reverse position, the opening of the resistor contactors, the directional contactors and the opening of the relays 42 and 39 will be almost simultaneous.

When the master controller reaches the first reverse position, the directional contactors 29 and 30 will be closed, and the winding 40 of the relay 39 will be shunted through the auxiliary contacts 59 of the contactor 29. The relay 39 will not close its contacts until the current in the motor armature circuit has decreased to a predetermined value, at which time the winding 41 is sufficiently reduced in energization so that the relay may close. The closing of the plugging contactor 34 as a result of the closing of the relay 39 will effect the shunting of the winding of the relay 42 as before, and this relay will introduce the same time interval between the operation of the plugging contactor 34 and the accelerating contactor 39, as was previously the case for forward motor operation. The accelerating contactor 38 will close promptly after the closing of the contactor 37 in the manner previously explained.

It will be observed that I have provided a very simple and effective time element relay which depends for its time of operation on the invariable time required for the holding

effect of the flux of the relay when the winding of the relay is shunted. The operation of the relay contact from and to the closed position is entirely under the control of the flux set up by the winding of the relay. The relay is of itself a very simple, effective and reliable device, and one which can be manufactured in large scale production for a materially lower cost than other time element devices 5 with which I am familiar. The provision of the simple, effective and reliable adjusting devices of the relay afford means whereby the time interval may be very accurately adjusted to the exact time desired, and as before stated, 10 this determined time interval will be invariable for all practical purposes. This electromagnetic time element relay is covered in a divisional application, Serial No. 125,112, filed July 26, 1926. It will also be observed 15 that the control system in which I employ the time interval relay for obtaining the desired time interval of operation between the closing of the plugging contactor 34 and the accelerating contactor 37 is very simple, thus tending toward a great reliability of operation. 20

What I claim as new and desire to secure by Letters Patent of the United States, is:

1. In combination, a motor controlling switch, a motor controlling resistor, a contactor for shunting the resistor, and a normally closed electromagnetic time element relay for controlling said contactor to control the shunting of the resistor a definite interval of time after the closing of said switch, the winding of said relay being connected to be shunted at the same time that the said switch is closed and the time element of operation of the relay being effected solely by the inductance of the relay. 30
2. In combination, two motor controlling contactors, an electromagnetic time element relay for delaying the energization of the second of said contactors for an interval of time after the closing of the first of said contactors, the said relay having a winding which is connected to be energized to open the relay quickly against its bias to the closed position when the first contactor is 35 open and to be shunted when the first contactor closes, the operation of said relay to the closed position and the time interval introduced thereby in moving from the open to the closed position being determined solely by the inductance of the relay. 45
3. In combination, in a system of motor control, a pair of directional switches, a plugging resistor, a contactor for shunting said resistor, a single relay for controlling the 50

closing of the plugging contactor, the said relay having two windings which cooperate to open the relay and hold the same in the open position, one of said windings being connected to be energized when said directional switches are open and to be shunted by the closing of either of said directional switches, and the other of said windings being connected to regulate the closing of the relay in accordance with the motor current, a time interval after the shunting of said first 60 winding. 70

4. In combination, in a system of motor control, a pair of directional switches, a plugging resistor and an accelerating resistor, a contactor for shunting each of said resistors, 75 a single plugging relay for controlling the closing of the plugging contactor, the said relay having two windings, which cooperate to open and hold the relay in the open position, one of said windings being connected to be energized when said directional switches are opened and to be shunted by the closing of either of said directional switches, the said other relay winding being connected to regulate the closing of the relay in accordance with 80 the motor current an interval of time after the closing of either directional switch, and a single winding normally closed time element relay for controlling said accelerating contactor, the winding of said accelerating relay 85 being connected to be energized to open said relay when said directional switches are open and to be shunted by the closing of said plugging contactor to delay the closing of the relay and the closing of the accelerating contactor for a definite interval of time after the closing of the plugging contactor. 95

5. In combination, two motor controlling switching mechanisms, the second switching mechanism being biased to closed position, 100 and means for delaying the deenergization of the second switching mechanism for an interval of time after the closing of the first switching mechanism including a winding on said second switching mechanism connected to be energized to open said switching mechanism quickly against its bias when the first switching mechanism is open and to be shunted when the first switching mechanism closes, whereby a time interval determined 105 solely by the inductance of said winding is introduced in the closing of the second switching mechanism in accordance with its bias. 110

In witness whereof, I have hereunto set my hand this 2nd day of May, 1925.

GEORGE B. STARIE.
